UNITED STATES PATENT OFFICE

WILLIAM F. KAPP, OF ELMHURST, ILLINOIS, ASSIGNOR TO ASSOCIATED ELECTRIC LABORATORIES, INC., OF CHICAGO, ILLINOIS, A CORPORATION OF DELAWARE

TELEPHONE SYSTEM

Application filed March 25, 1932. Serial No. 601,146.

This invention relates in general to automatic telephone systems, and its object, broadly stated, is to provide a new and improved common-talking, selective-signalling system. 5 More specifically, the object of the invention is to provide an efficient yet inexpensive system for small private installations, such as schools, banks, and similar places, where there is no great need for holding more than one 10 conversation at a time.

Another object of the invention is to provide a new and improved arrangement for generating the ringing current in small telephone systems. In small telephone systems 15 wherein the installation of a ringing current generator of the usual type is unwarranted, arrangements have been provided heretofore for generating ringing current by the operation of the calling subscriber's dial. In these 20 systems, however, the ringing current produced is of a very low frequency, corresponding to the frequency of the dial impulses, which are ordinarily transmitted at the rate of ten impulses a second. In the present system, ringing current generation is controlled 25 in the same manner pointed out above; that is, by means of the calling subscriber's dial. However, arrangements have been provided for increasing the frequency of the generated 30 ringing current so that it is much higher than has been possible heretofore with this type of ringing. This results in a very satisfactory ringing signal for the wanted subscriber, and is a decided improvement over the prior 35 systems.

The above pointed out objects, together with others not specifically mentioned at this time, will appear more fully in the specification which is to follow.

40 Referring now to the drawing, there is illustrated therein, by means of the usual circuit diagrams, sufficient of the apparatus in a system embodying the principles of the invention to enable the invention to be thoroughly understood.

The automatic substation A, B, and C, shown therein, which are substations of the same common-talking private automatic exchange, are ordinary automatic substations 45 having the usual talking and signalling in-

strumentalities and having in addition the calling devices CD, CD1, and CD2, respectively, for the purpose of controlling the switching mechanism SM. The rotary switch SM is of the well-known, single-level, step-by-step type. Its wipers 38 and 39 are advanced step by step under control of combination battery-feed and line relay 23 to select a conductor extending to the ringer of the wanted-subscriber's substation. The transformer T and differential relay 27 are provided for the purpose of generating the ringing current for signalling the wanted subscriber. 55

A brief description of the apparatus having been given, the operation will be explained more in detail. For this purpose, it will be assumed that the subscriber at substation A desires to call the subscriber at substation C, whose substation is connected to 60 the same common-talking line. In order to do this, the subscriber at substation A removes his receiver and then dials the number of the subscriber at substation C. 65

When the receiver is removed at substation A, line relay 23 energizes over line conductors 21 and 22. Upon energizing, line relay 23 completes a circuit for the slow-acting release relay 24. At armature 30, release relay 24 opens a point in the restoring 70 circuit and prepares a circuit for the slow-acting series relay 25 and the rotary magnet 28. 75

The calling subscriber at substation A may 80 now proceed to operate his calling device 85 CD in accordance with the digit 3, comprising the desired subscriber's number. As a result, three interruptions are produced in the circuit of the line relay 23. In response 90 to the first deenergization of line relay 23, an impulse of current is transmitted at armature 29 to the slow-acting series relay 25 and rotary magnet 28 through the operated armature 30 and wiper 38 of the rotary switch SM 95 in its normal or home position. The slow-acting series relay 25 and the rotary magnet 28 energizes in series over this circuit. Series relay 25, upon energizing, prepares a new circuit path for itself and the rotary magnet 28 100 105 110 115 120 125 130 135 140 145 150 155 160

at armature 31, at the same time opening a point in the circuit of relay 26.

Line relay 23 energizes again at the end of the first impulse and again completes the 5 circuit of slow-acting release relay 24 as well as opening the initial energizing circuit of the series relay 25 and the rotary magnet 28. The series relay 25, being slow releasing, remains in its operated position, but the rotary 10 magnet 28 falls back, thereby advancing its wipers 38 and 39 into engagement with the first set of bank contacts.

In response to each succeeding momentary 15 interruption constituting the digit 3, line relay 23 again restores and completes a circuit for series relay 25 and the rotary magnet 28 at armature 29 and its resting contact. Since wiper 38 has been advanced from its home position, the circuit for series relay 25 and 20 rotary magnet 28 now includes the operated armature 31. The series relay 25 accordingly remains operated, and the rotary magnet 28 responds by advancing the wipers 38 and 39 two more steps into engagement with the 25 third set of bank contacts.

At the termination of the impulse series, line relay 23 remains in its energized position and maintains release relay 24 energized. However, the slow-to-release series relay 25 30 soon falls back and transfers the impulsive circuit to the slow-to-release, ringing-control relay 26.

The switching mechanism SM is now in a 35 position to respond to impulses, constituting the digit 0, for example, transmitted by the calling subscriber at substation A, to transmit ringing current over wiper 39 and conductor 43 to operate the ringer at the called substation C. The signalling of the called 40 subscriber is accomplished in the following manner:

When the calling subscriber dials the ringing digit 0, line relay 23 is momentarily restored ten times. Each time line relay 23 45 falls back, it completes the impulse circuit which has been extended by way of armature 31 to relay 26. Relay 26, therefore, operates and remains operated throughout the series of impulses. At armatures 32 and 33, 50 relay 26 connects the windings of differential relay 27 to the front and back contacts, respectively, of armature 29.

When relay 26 connects up the windings of 55 relay 27, relay 23 being in a restored condition, relay 27 is at once operated through its upper winding. The closing of the front contact of armature 34 of relay 26 results in the closure of a circuit for the right-hand primary winding of transformer T, by way of resistance 40 and armature 34 of relay 26.

When line relay 23 again energizes at the 60 termination of the momentary interruption of its circuit, at armature 29 it opens the circuit of the upper winding of differential relay 27, and completes a circuit for the low-

er winding of the relay. Responsive to the opening of the circuit of its upper winding, relay 27 starts to become demagnetized. Moreover, the relay starts to become magnetized in the opposite direction responsive to current flow in its lower winding. Therefore, armature 35 will restore and engage its resting contact while the magnetism is passing through the zero point (while reversing in direction), thereby completing a circuit for the left-hand primary winding of transformer T by way of resistance 40. 70 75

The magnetism generated by the lower winding of relay 27 eventually becomes strong enough to reoperate armature 35, whereupon the circuit is transferred from the left-hand winding of the transformer T, to the right-hand winding. Since each winding of relay 27 opposes the other, it is evident that relay 27 is caused to restore and reoperate each time armature 29 of relay 23 is released or attracted. 80 85

This operation continues until the line relay has been momentarily deenergized ten times responsive to the dialling of the digit 0, with the result that the differential relay 27 has been momentarily energized twenty times. Relay 26 now releases and disconnects the windings of relay 27 at armatures 32 and 33, while at armature 34 it opens the 90 primary circuit at transformer T. 95

The first time armature 35 and its front contact is closed, the current flow through the right-hand, primary winding of transformer T causes an induced current to be 100 generated in one direction in the secondary winding of the transformer. Responsive to the opening of this circuit and to the closely following closure of the circuit through the left-hand, primary winding, an induced current is generated in the other direction in the secondary winding of transformer T. Each time line relay 27 changes position, the magnetism in the transformer is reversed and a half cycle of current is generated in the secondary winding. Since relay 27 operates ten times and restores ten times, twenty cycles of alternating current are generated in the 105 secondary winding of the transformer. 110

Responsive to the alternating current generated by the opening and closing of the circuit through the right- and left-hand, primary windings of transformer T, the bell at substation C vibrates. The circuit in which the induced alternating current flows is as follows: ground, secondary winding of transformer T, wiper 39 and its engaged third bank contact, conductor 43, condenser and ringer at substation C, switchhook, lower line conductor 22, and the lower winding of line relay 23, to ground. 115 120 125

If the subscriber at substation C does not answer the call, the subscriber at substation A may resign him by again dialling the digit 0. The switching mechanism SM will 130

respond in the manner described above to cause the transmission of induced alternating current by way of the secondary winding of transformer T to again ring the bell 5 at the substation C.

When the subscriber at substation C removes his receiver to answer the call, the 10 ringer is disconnected and his transmitter and receiver are bridged across the line conductors 21 and 22, so that the conversation between the subscriber at substation A and substation C may now take place. Should either subscriber inadvertently operate his calling device at the present time, it will have 15 no effect on the switch SM, since the line relay will not follow the dial at one station with the receiver removed at another station.

Talking current for the calling and called 20 subscriber is supplied from the windings of line relay 23. The talking path is indicated by the heavy conductors.

When the conversation is finished, both 25 subscribers replace their receivers. When the last party has replaced his receiver, the circuit for line relay 23 is opened. Upon deenergizing, line relay 23 breaks the circuit for release relay 24, which subsequently deenergizes and completes a circuit for operating 30 the rotary magnet 28 to restore its wipers to their normal or home position. The circuit for restoring the wipers to normal or home position is as follows: ground, armature 29 and its resting contact, armature 30 and its resting contact, off-normal contact 37 (closed on the first step of the wipers of the switch), self-interrupting contact 36, winding of the rotary magnet 28, to battery. Rotary magnet 28 energizes over this circuit, 35 and upon energizing opens its initial energizing circuit at its self-interrupting contacts 36. This opens the circuit for the rotary magnet and causes it to deenergize and advance its wipers to the next bank contact. 40 When the self-interrupting contacts restore, the circuit is again completed for energizing the magnet, which accordingly responds and opens its energizing circuit again at its self-interrupting contacts 36 and advances the 45 wipers another step. The advancement of the wipers continues until the wipers of the switch are advanced to their home position, at which position the off-normal contacts 37 are opened and the switch is accordingly 50 brought to rest.

When the subscriber at substation C desires to establish a connection with the subscriber at substation B, for example, he will 55 remove his receiver and dial the digit 2, which will cause the wipers of the switch SM to be advanced to their associated second bank contacts to engage conductor 42. The subscriber will now dial the digit 0, or any other desired 60 ringing digit, which will cause the ringer at substation B to respond in the manner previ-

ously described. The restoration of the switch to normal after the subscribers have replaced their receivers takes place as previously described.

What is claimed is:

1. In a telephone system, a common talking line provided with a plurality of subscribers' stations, a plurality of individual signalling conductors, a switch, means controlled from one of said stations for operating said switch to connect with any one of said conductors, and means controlled by the operation of the calling subscriber's dial after said connection has been established for transmitting signalling current over the connected conductor to signal the wanted subscriber on said line.

2. In a telephone system, the combination with a common talking line provided with a plurality of subscribers' stations, of an automatic switch, a plurality of individual signalling conductors extending to said stations, respectively, means controlled over said line for connecting said switch to any one of said signalling conductors, and means controlled over said line after said signalling conductor has been connected for generating alternating current for operating the signal at the station individual to that conductor.

3. In an automatic telephone system, a common talking line, a plurality of subscribers' stations, signalling conductors individual to each of said stations, a switch operated under control of the dial at the calling subscriber's station to select the wanted subscriber's signalling conductor, and signalling means operated under control of the calling subscriber's dial for generating signalling current to operate the signal at the wanted subscriber's station over the selected conductor.

4. In an automatic telephone system, an automatic switch, a signalling conductor, means for operating said switch to connect up to said conductor, and directly-controlled means in said switch for generating signalling current, said generating means comprising a differential relay and a transformer.

5. In a telephone system, a line terminating at a common switching point, a plurality of subscribers' stations on said line, individual signalling conductors extending from said common switching point to said stations, respectively, ringing-current generating means directly controlled by a calling subscriber, and a signalling circuit for each of said stations including the secondary winding of said transformer and the individual signalling conductor of the station in series.

6. In combination with a plurality of telephone stations having common talking and individual ringing conductors, a connector, means responsive to the impulses of a first digit for operating the connector over said common talking conductors to select a desired ringing conductor, and means responsive to

- the impulses of a second digit for generating alternating current and for transmitting the current over said ringing conductor to signal a wanted subscriber.
- 5 7. In an automatic telephone system, a common talking line terminating in an automatic switch, a line relay in said switch operated under control of the calling subscriber, individual conductors from each of said 10 stations, respectively, terminating in said switch, means responsive to the operation of said line relay for advancing said automatic switch to select one of said signalling conductors, a differential relay, and means responsive after the termination of said selecting 15 operation for controlling said differential relay to transmit alternating current over the selected signalling conductor to operate the ringer at the wanted subscriber's 20 station, said differential relay being operated under control of said line relay and responding twice as many times as the line relay responds to the impulses dialled by the calling subscriber.
- 25 8. In a telephone system, an automatic switch, a plurality of subscribers connected to a common-talking line, an individual signalling conductor for each of said subscribers, means at said stations for transmitting 30 impulses over said line to operate said switch to select one of said conductors and for then transmitting impulses for generating alternating current to signal the subscriber individual to said conductor, and means for causing 35 said current to have a frequency double the frequency of the impulses transmitted to generate it.
- 40 9. A switching device, means for transmitting series of impulses of a particular frequency to said device, means in the device responsive to one series of impulses for setting the device, and means in the device responsive to a subsequent series of impulses 45 for generating an alternating current of a frequency greater than the frequency of the received impulses.
- 45 10. A switching device, means for transmitting series of impulses of a particular frequency to said device, means in the device responsive to one series of impulses for setting the device, and means in the device responsive to a subsequent series of impulses 50 for generating an alternating current whose frequency is double the frequency of the impulses of the subsequent series.
- 55 11. A switching device, means for transmitting series of impulses of a particular frequency to said device, means in the device responsive to one series of impulses for setting 60 the device, and means in the device responsive to a subsequent series of impulses for generating an alternating current of a frequency which is a multiple of the frequency of the impulses of the subsequent series.
- 65 12. In an automatic switch, a line relay controlled by impulses from a calling subscriber, a magnet operated responsive to said impulses to set said switch, and means controlled by said line relay responsive to subsequent impulses for generating a signalling current having a greater frequency than the frequency of the impulses received by said line relay.
- 70 13. In a telephone system, an automatic switch, a plurality of subscribers' stations connected to a common line, an individual signalling conductor for each of said stations, and means at said stations for transmitting impulses over said line to operate said switch to select one of said conductors and for transmitting impulses for generating ringing current to signal the subscriber individual to said conductor, said current having twice the frequency of the impulses transmitted to generate the same.
- 75 14. In a telephone system, a common talking line provided with a plurality of subscribers' stations, a plurality of individual signalling conductors, an automatic switch, means controlled from one of said stations for operating said switch to connect to any one of said conductors, and means in said switch directly operated from said station for generating twenty-cycle ringing current to signal the wanted subscriber over the selected conductor.
- 80 15. In an automatic telephone system, a common talking line having a plurality of subscribers' stations thereon, an automatic switch, individual signalling conductors, means at said stations for controlling said switch to select one of said conductors, and means responsive to a subsequent operation of said controlling means for generating alternating current to operate a signal at the wanted subscriber's station over the selected conductor.
- 85 16. In a telephone system, a common talking line provided with a plurality of subscribers' stations, a plurality of individual signalling conductors, an automatic switch controlled over said line by a calling subscriber to select one of said conductors, a transformer, means for opening and closing a circuit including the primary winding of said transformer, said means operated under control of said calling subscriber, and a signal connected to the selected signalling conductor operated responsive to the induced current generated in the secondary winding of the transformer by the opening and closing of the circuit including the primary winding to signal the subscriber at the wanted station.
- 90 17. In a telephone system, a plurality of subscribers' stations having common talking and individual ringing conductors, an automatic switch controlled over the common talking conductors by a calling subscriber to select the ringing conductor of the wanted
- 95 100 105 110 115 120 125 130

subscriber, a transformer having its primary winding divided into two sections, a circuit for each of said sections, a relay controlled by said calling subscriber after the selection 5 of said ringing conductor for rapidly opening and closing said circuits, and a signal at the wanted subscriber's station connected to said conductor operated responsive to the current induced in the secondary winding of 10 said transformer by the opening and closing of said circuits.

18. In an automatic switch, a magnet, means responsive to a first series of impulses transmitted by a calling subscriber for operating 15 said magnet to select a wanted subscriber, and means responsive to a second series of impulses for generating alternating current for signalling the selected subscriber.

20 19. In a signalling system, an impulse receiving device, an alternating current generator, and means controlled by said device for causing said generator to generate alternating current of a frequency greater than the 25 frequency of the received impulses.

20. In a signalling system, an impulse receiving device, a transformer arranged to deliver current impulses of a frequency double the frequency of the received impulses, control 30 means interposed between said device and said transformer, means for causing said control means to be operated twice each time an impulse is received by said device, and means including circuit connections controlled 35 by said control means for causing said transformer to deliver said current impulses.

In witness whereof, I hereunto subscribe my name this 18th day of March, 1932.

40 WILLIAM F. KAPP.
